UNITED STATES PATENT OFFICE.

THOMAS BROWN, OF CLEVELAND, OHIO.

IMPROVEMENT IN FIRE-PLACE GRATES.

Specification forming part of Letters Patent No. 177,464, dated May 16, 1876; application filed October 1, 1873.

To all whom it may concern:

Be it known that I, THOMAS BROWN, of Cleveland, in the county of Cuyahoga and State of Ohio, have invented a new and useful Improvement in Fire-Place Grates; and I do hereby declare that the following is a full and exact description of the same, reference being had to the accompanying drawings, and to the letters of reference marked thereon.

This invention is a fire-place grate of peculiar construction, consisting mainly of a series of bars of uniform length and shape, which are all secured in the same inclined plane, as will be fully described hereinafter.

In the drawings, Figure 1 represents a side view of the grate as applied to a fire-place; Fig. 2, a side elevation, and Fig. 3 a perspective view, of the grate, taken from the rear side.

To enable others skilled in the art to make and use my invention, I will now proceed to describe fully the manner of constructing the same.

a a represent bars of equal length, all of which are bent alike, and united at the top to the cross-bar *A*, and at the bottom to cross-bar *B*, as shown.

The bar *A* has arms *a' a'* pendent at right angles thereto, the lower ends of which are united to the side bars of the series by tie-bars *c c*, as shown.

d d represent hooks attached to the inner side of the arms *a' a'*, by means of which the grate is secured in place. *e e* represent V-shaped irons, by means of which the adjacent bars of the series are secured to each other, the same being arranged alternately above and below the horizontal center-line, as shown.

The grate is supported in the fire-place by means of a supporting pin or hook at its lower part, and the hooks *d d* above, which are caught over any suitable pin or projection, as shown.

The advantages of the described construction are quite marked.

The bars are held in the same inclined plane, so that no corners are formed for the accumulation of ashes and cinders. The bars are so united that they are free to expand under the influence of heat.

The projection of the V-shaped bars into the coal-space serves to loosen up the fuel, prevent it from clogging, and permit the air to reach it readily and insure its perfect combustion.

The inclination of the bars is such that the fire is more exposed than when the bars are held in vertical lines, and the heat is radiated from it in such manner that the floor is reached by the rays emanating from the lowest part of the grate. It causes a bright, clear fire; the ashes do not clog; no poking is needed, and all the heating-surface is brought to the air.

Having thus described my invention, what I claim as new, and desire to secure by Letters Patent, is—

1. In an open fire-place grate adapted to have its entire front exposed to view, the combination of the inclined bars *a* and inwardly-projecting V-shaped irons *e*, arranged at regular intervals, and operating, by the settling of the fuel, as permanent poker to loosen up the said fuel and keep the front of the grate clear and bright, substantially as described.

2. In an open fire-place grate adapted to have its entire front exposed to view, the combination of the bars *A B*, inclined bars *a*, and projecting V-shaped irons *e*, substantially as described and shown.

3. In combination with a grate having inclined bars, the vertical pieces *a'* united to the cross-bars *A*, and the end inclined bar of the series, as described.

This specification signed and witnessed this 24th day of September, 1873.

THOS. BROWN.
